Filed Feb. 14, 1967, Ser. No. 5,811

Term of patent 14 years

(Cl. D48—4)

FIGURE 1 is a perspective view of a lamp, showing my design;

FIGURE 2 is a front view in elevation of the lamp shown in FIGURE 1;

FIGURE 3 is a back view in elevation of the lamp shown in FIGURE 1;

FIGURE 4 is a top view taken along line 4-4 of FIGURE 3;

FIGURE 5 is a perspective view of another embodiment of a lamp showing my design;

FIGURE 6 is a perspective view of still another embodiment of a lamp showing my design;

FIGURE 7 is a front view in elevation of the lamp shown in FIGURE 6;

FIGURE 8 is a back view in elevation of the lamp shown in FIGURE 6;

FIGURE 9 is a top view taken along line 9-9 of FIGURE 8; and

FIGURE 10 is a perspective view of still another embodiment of a lamp showing my design.

The dominant features of my design reside in the portions shown in full lines. The broken line showings of support elements in FIGS. 1, 3 and 5 and the fragmentary showings of a support pole in FIGS. 6 and 10 are for illustrative purposes only.

What is claimed is:

The ornamental design of a lamp, substantially as shown and described.
